UNITED STATES PATENT OFFICE.

JOSEPH HONIG, OF NEW YORK, N. Y.

WATCH-PROTECTING DEVICE.

Application filed August 15, 1924. Serial No. 732,258.

To all whom it may concern:

Be it known that I, JOSEPH HONIG, citizen of Hungary, residing at New York city, in the county of New York and State of New York, have invented certain new and useful Improvements in Watch-Protecting Devices, of which the following is a specification.

This invention relates to a watch protecting device which is adapted to form a link inserted between the chain and the watch ring to prevent the watch being withdrawn from the pocket when the chain is pulled by a pickpocket, thereby ensuring against loss of the watch by theft while being worn.

The invention has for an object the provision of a novel and simple device of the type above set forth.

For further comprehension of the invention, and of the objects and advantages thereof, reference will be had to the following description and accompanying drawing, and to the appended claims in which the various novel features of the invention are more particularly set forth.

Fig. 1 of the drawing is a side view showing my improved device as applied between a watch and its chain.

Fig. 2 is a central longitudinal view of the device.

Fig. 3 is a transverse sectional view of the device this view being taken on the line 3—3 of Fig. 2.

Fig. 4 is a part side view and part longitudinal sectional view.

Fig. 5 is a fragmentary central longitudinal sectional view taken at right angles to Fig. 1.

As here embodied my improved device comprises a cup shaped casing 10 which is formed at one end with an integral bottom or closure. At its other end this casing has fixed thereon a cap 11 provided with a depending flange 12 that overlaps the edge of the casing and may be crimped thereon, or may be screwed to the casing as indicated in Fig. 4 of the drawing. This cap is formed with a central aperture 14 through which extends a plunger pin 15 that has a ring 16 on its outer end, this ring being adapted to have the watch chain 17 attached thereto. A second ring 18 is attached to the casing 10 at its integrally closed end and may be engaged with the usual ring 19 on the watch 20.

The plunger pin 15 has pivotally attached

to its inner end a series of prongs 23, these prongs being pivotally attached to the pin at one end and extending at opposite ends into apertures 24 in the cap 11. There are three of these prongs here shown, suitably spaced around the pin 15, although the number might be varied if desired. As a convenient method of hinging or pivoting the prongs 23 to the pin 15 the latter is formed with a number of grooves such as 25 in the inner end thereof of which receive the bowed inner ends 23' of the prongs 23, these inner end elements 23' being prevented from displacement from the grooves 25 by a ring 26, that encircles the pin 15. The pin 15 has a radial flange 27 on its inner end that prevents longitudinal displacement of the ring. Surrounding the pin 15, within the casing 10, is a coiled expansion spring 30 that bears at one end on the cap 11 and at its other end against the inner end portions of the prongs 23. This spring 30 serves to retain the pin 15 in its inwardly projected position, with the tips of the prongs 23 just engaged in the apertures 24 in the cap 11. These apertures 24 in the cap are spaced radially some distance from the pin 15 so that normally the prongs diverge from the pin, and as will be obvious, when the pin is pulled outward in the casing the prongs are both projected from the cap 11 in a longitudinal direction but are caused to diverge at a greater angle from the pin so that their points spread beyond the confines of the casing and enter into the walls of the pocket in which the watch is carried. It is believed that the manner of use of my improved device will be readily understood from the above description, it being apparent that if the chain 17 is pulled in the endeavor to remove the watch from the pocket the pin 15 will be moved outward in the casing 10 and the prongs 23 caused to emerge and engage in the pocket walls. The user of the watch can remove the same by reaching into the pocket and grasping the casing.

As shown most clearly in Fig. 5 of the drawing the casing 10 has an inwardly projecting boss 35 formed on one side which serves to guide and support a locking bolt 36 that may be moved to project its inner end into a circumferential groove 15^a in the plunger pin 15 to lock the latter against outward movement. The bolt 36 has fixed thereto a pin 37 that engages in a helical

slot 38 in the boss 35 this slot having its inward end formed with a backturned notch 38'. Surrounding the bolt 36 outside the casing is a coiled expansion spring 39 that 5 bears outwardly on the enlarged head 40 of the bolt. When the owner of the watch is in surroundings where there is no danger of theft he can lock the pin 15 against movement by turning the bolt 36 until the pin 37 10 engages in the notch 38' when the inner end of the bolt will be projected into the groove 15^a in the pin 15.

While I have described my protecting device to be used for watches, it is to be understood that I reserve the rights to its use 15 also in connection with other objects which are to be protected, such as keys, chained purses and the like.

Having thus described my invention, 20 what I claim as new and desire to protect by Letters Patent of the United States is as follows:—

1. In combination with a watch and chain, a longitudinally expansible link 25 forming the connecting medium between the watch and the chain, said link comprising a cylindrical casing closed at both ends, a plunger pin extending longitudinally in said casing and projecting at one end 30 through one end of the casing, and a series of prongs pivotally connected at one end to the inner end of said plunger pin and engaging at their opposite ends in apertures in the said end of the casing, and a dis- 35 placeable locking bolt projected through the

side of said casing to engage and lock said plunger pin.

2. In combination with a watch and chain, a longitudinally expansible link forming the connecting medium between the 40 watch and the chain, said link comprising a cylindrical casing closed at both ends, a plunger pin extending longitudinally in said casing and projecting at one end through one end of the casing and formed 45 between its ends with a circumferential groove, a series of prongs pivotally connected at one end to the inner end of said plunger pin and engaging at their other ends in apertures in the said end of the casing, a spring surrounding the said plunger pin to retain the latter retracted into the casing with the points of said prongs confined within the casing, a hollow boss 50 formed on the side of said casing, a bolt slidably and rotatably mounted in the said boss and projecting through the side wall of the casing with its inner end registering with the said groove in the plunger pin, a pin fixed to the said bolt and engaging in 55 a helical slot in the said boss, said slot having an offset notch in one end, and a spring surrounding the bolt and acting to retain the said pin engaged in the said notch when the bolt is engaged in the said groove to 60 retain the bolt in the said position.

In testimony whereof I have affixed my signature.

JOSEPH HONIG.
